UNITED STATES PATENT OFFICE

168,091

COMBINED BARBECUE STAND AND LAZY SUSAN

Ardie M. Fort, Los Angeles, Calif.

Application May 24, 1952, Serial No. 19,880

Term of patent 14 years

(Cl. D81—10)

To all whom it may concern:

Be it known that I, Ardie M. Fort, a citizen of the United States, residing as Los Angeles, California, have invented a new, original, and ornamental Design for a Combined Barbecue Stand and Lazy Susan, of which the following is a specification, reference being had to the accompanying drawing, forming a part thereof.

I claim:

The ornamental design for a combined barbecue stand and lazy susan, as shown.

ARDIE M. FORT.
